ARTHUR E. PEW, JR., OF BRYN MAWR, PENNSYLVANIA, ASSIGNOR TO SUN OIL COMPANY, OF PHILADELPHIA, PENNSYLVANIA, A CORPORATION OF NEW JERSEY

PROCESS OF DISTILLING OIL

Application filed January 8, 1927. Serial No. 159,754.

In the distillation of lubricating oil, it is necessary to heat the oil to be distilled to a temperature so high that it is partly decomposed, thereby producing distillates containing decomposition products that require expensive purification treatment to remove; and their complete removal can never be effected. It is, of course, well understood that by distilling oil under a partial vacuum, the distillation temperatures of the fractions to be distilled are materially reduced, thereby enabling the distillation to be effected at lower temperatures and hence with less decomposition. It is also well understood that as an absolute vacuum is approached the boiling points drop at a rate that rapidly and progressively increases, so that, if it were possible to reasonably closely approach an absolute vacuum, the boiling points of all except the heaviest fractions could be reduced to below the temperature at which any substantial amount of decomposition occurs. In distilling the high boiling point fractions, the highest vacuum that it is practicable, with modern engineering methods, to secure, is desirable. With a maximum practicable vacuum, it would be possible, if local overheating could be avoided, to distill crude oil practically down to asphalt or coke at such relatively low temperatures as to produce abnormally heavy and viscous lubricants that would contain so small a proportion of cracked products that they could be said to be almost free therefrom and would require no subsequent expensive purification treatment.

Known high vacuum distillation processes (so-called) do not, however, afford the conditions required to avoid the formation of decomposition products, and in some, if not all, cases, do not even succeed in securing the high vacuum that they are supposed to secure. Thus, in batch distillation, the absolute pressure above the body of oil might be an absolute vacuum, and yet the oil would actually vaporize at an absolute pressure substantially in excess of the minimum degree of vacuum which it is sought to obtain; for the reason that the hydrostatic pressure toward the bottom of the column, where vapor globules begin to form, is such that the vapor as it forms

is in fact subject to an absolute pressure substantially above the desired, intended and necessary absolute pressure. Not only does vaporization occur at a much higher temperature than that calculated to be necessary on the basis of the degree of vacuum above the oil body, but the vapor after it forms is subjected to such higher temperature, accompanied by the formation of such decomposition products as are produced at that temperature by cracking or otherwise.

It has also been proposed to run oil through a long tube in a liquid stream whose volume is much less than that of the tube, to heat the tube in the usual way by hot furnace gases, and to convey, through the tube, the vapors, formed during the passage of the oil through the tube, to a fractional condensing apparatus, whereby distillates of different cuts may be obtained. In this process, the vapors are not only forced to travel through the tube for a considerable distance in contact with the flowing oil, but such vapors, while they are in the tube, are subject to the heat of the heating medium (which, without an apparatus of undue size, owing to the low heat conductivity of hot gases, must be several hundred degrees higher than is necessary to produce the vapors), thus subjecting the oil vapors, as well as the liquid oil, to local overheating. In fact, the conditions required to avoid local overheating of the oil and cracking of oil vapors are not avoided at all, regardless of the degree of vacuum that may be obtained within the tubes. Moreover, in such process, the vapor is compelled to travel for a long distance through the tube to the outlet thereof. With a tube of reasonable diameter, it is impossible, in such an elongated stream of vapor, to avoid a substantial pressure drop from a point distant from the vapor exit to the vapor exit; and even though a condition of high vacuum may exist at the outlet end of the tube, the absolute pressure at points more or less distant from such outlet is substantially above that which it is sought to obtain and which it is necessary to obtain in order to satisfactorily distil the highest boiling point products.

I having succeeded in providing all the

conditions required to successfully practice a high vacuum process and have succeeded in converting the entire body of oil, except a small percentage of residual coke, into lubricants that require no subsequent expensive purification, and some of which possess characteristics heretofore wholly unknown.

The result obtained, however, is not due wholly to the perfection of the lubricating oil distillation process. Even when all the conditions required to successfully practice a high vacuum process are provided, it does not suffice to produce lubricating distillates free of cracked and oxidation products and without objectionable odor, and free from tendency to color deterioration. The finished distillates still contain certain of these impurities because of the content of odor-producing and color-deteriorating products in the crude oil or because of the breaking down of sulfur compounds incidental to the most perfect methods of preparing lubricating oil stock from the crude oil. Other cracked and oxidation products, as well as the impurities specified, are also certainly produced in ordinary processes of topping and otherwise treating crude oil for the production of lubricating oil stock and are, in fact, produced by all such processes known to me. Among the factors that tend to the production of an imperfect lubricating stock may be mentioned high or prolonged temperature conditions, access of atmospheric air, and imperfect methods of adding acid neutralizing solutions including imperfect subsequent dehydration.

I have succeeded, not only in perfecting the lubricating oil distillation process per se, but also in providing all the conditions required to produce a lubricating oil stock substantially free of all impurities except certain odor-producing and color-deteriorating products, of which at least some are believed to be present in the crude. These inevitable impurities, however, I have succeeded in eliminating from the finished distillates without the use of any known separate and relatively expensive purification process but by an automatically acting deodorizing process partly merged with and partly supplemental to the distillation process.

The principal conditions whereby I secure the results sought may be enumerated as follows:

(1) The separation of the lubricating oil stock from the crude oil by so confining the oil against access of oxygen, by subjecting the oil, in the necessary distilling operations, to such conditions of limited temperature and pressure as to avoid or minimize cracking, and by so adding an acid neutralizing solution with subsequent effective dehydration, as to produce a lubricating oil stock substantially free of all impurities except certain odor-producing products.

(2) The maintenance above the lubricating oil stock, while it is being heated (except in the distillation of relatively low boiling fractions) of a vacuum of not lower than substantially twenty-nine inches, that is, an absolute pressure not higher than twenty-five millimeters mercury. It is preferred, however, to reduce the absolute pressure to as nearly an absolute vacuum as is practicable, particularly in distilling the higher boiling fractions. It is practicable to secure a substantially higher vacuum than that specified.

(3) The avoidance of a column of oil of any substantial height, thereby making the factor of hydrostatic pressure negligible.

(4) The maintenance of the smallest practicable temperature difference between the oil and the heating medium, in the distillation of the higher boiling lubricating fractions, so as to avoid local overheating.

(5) The application of heat, principally if not wholly, to only the liquid oil, and the avoidance of conditions whereby the vapors when formed continue to be subject to the temperature conditions required to form them; or, in other words, the maintenance of conditions under which the vapors tend to cool from the moment they leave the surface of the oil body.

(6) The avoidance of prolonged contact between the liquid oil being heated and the vapors that have escaped therefrom, which is accomplished by immediately withdrawing them from the locus of vaporization to a locus of condensation.

(7) The subsequent deodorization of the condensed oil.

The entire process, including the preparation of the lubricating oil stock from the crude oil, is a unitary process, in that every essential step contributes to the production of the ultimate pure product sought. The preparatory steps of my process preferentially involve the topping of the crude to recover the lighter hydrocarbons, principally gasoline, at a non-cracking temperature; the addition, as known in the art, of caustic soda or other suitable equivalent to neutralize certain organic compounds contained in the crude oil or produced in the subsequent distillation process; the evaporation of the water introduced with the soda; and the evaporation of other hydrocarbons, principally gas oil, which are heavier than gasoline and lighter than the lubricating fractions. These operations are so conducted that the residual oil is in ideal condition for distillation into lubricating oils, being substantially or entirely free from products of oxidation and cracking.

An apparatus suitable for carrying out my improved process is shown in the drawings, in which—

Fig. 1 is a diagram, in side elevation, of a

part of a complete lubricating oil distillation plant.

Fig. 2 is an end elevation of the same.

Fig. 3 is a diagrammatic view of the oil heating apparatus.

Fig. 4 is an elevational view of one of the units of the condensing, refluxing and deodorizing apparatus.

Figs. 5A and 5B represent a diagrammatic view of the part of the plant wherein the crude oil is distilled to prepare distillates for use as lubricating stock.

I shall first describe my preferred process of treating the crude oil to prepare the oil for my process of distilling the lubricating fractions, as conducted in the apparatus shown in Figs. 5A and 5B.

Crude oil is pumped through pump 61 and line 62 through the tubes in reflux condenser 63. Here the crude is raised in temperature about 20° F. by heat exchange with the vapors from tower 78. The rise in temperature will vary with the grade of crude and the amount of vapors coming off the towers.

The heated crude, continuing its passage through line 62, goes to reflux condenser 64, where it is heated to (say) 140° F. by heat exchange with the vapors from tower 90.

The crude then passes through heat exchanger 65, where it is in heat exchange relationship with residual oil, as hereafter described. Leaving this heat exchanger at a temperature of (say) 310° F., the crude then passes to a baffle tank 67 held under a pressure of (say) 100 pounds gauge. This tank is of such a size that the oil flows through at a velocity preferably not exceeding about 25 ft. per hour. At this velocity, and at the last mentioned temperature and pressure, the salt water contained in the crude, which may

amount to about two per cent., or over, settles to the bottom of the tank, where it is drawn off through draw-off pipes 68. By removing the salt water, subsequent troubles due to salt deposit are eliminated, thus greatly simplifying the problem of continuously running the process with avoidance of frequent shutdowns for cleaning the tubes of the pipe stills. The removal of the salt also enables a better grade of asphalt (if the crude has an asphalt base) to be obtained at a final stage of the lubricating oil distillation process; such asphalt having superior solubility tests, i. e., containing a relatively small percentage of insoluble material.

The oil from tank 67 flows through the tubes 70 and 71 of a pipe still and thence into a vaporizer 75 at a temperature of (say) approximately 450° F. This pipe still may be of conventional design, fuel oil being burned through burner 137 in space 72, the products of combustion passing upwards over tubes 70, down over tubes 71, into flue 73, and thence up stack 74. In order to keep the gas temperature low in this furnace, the

exhaust gases from pipe still 84—85 pass through flue 100 into the fire box 72 and are mixed with the products of combustion from burner 137. This results in great economy of operation, as it enables the hotter gases from pipe still 84—85 to give up their heat in pipe still 70—71. The flue gas temperature in flue 73 is not above about 400° F.

The pressure in vaporizer 75 being substantially atmospheric, vapors are freed from the incoming oil as it travels down over the inclined pans. These vapors pass upwards through manifold 76, distributor section 77 and packed section 78, and out vapor line 79 into reflux condenser 63. In the latter, the vapors are condensed, the condensate being returned through line 80 to the tower, or through line 81 to storage, in such proportions as the operation of the tower requires; an increased amount being returned through line 80 when a lighter product through line 81 is desired and a decreased amount when a heavier product is desired. The reflux from section 78 is caught in section 77 and passes through line 91 to storage. The product through line 81 is light gasoline and the product through line 91 is an intermediate gasoline.

The residual or partially topped oil, which may be said to be a light mazout, leaving the bottom of vaporizer 75 passes through pump 82 and the tubes 84 and 85, wherein it is heated to approximately 590° F. At this temperature, it passes into vaporizing tower 88, which contains a packed section 90 and operates in a manner similar to vaporizer 75. The product from this vaporizer that leaves through line 93 is light gas oil, and that which escapes through line 92 is heavy gas oil.

The residual oil leaving the bottom of tower 88, which may be said to be an intermediate mazout, passes through pump 96 at a temperature of (say) 580° F. and through a heat exchanger 66, in which it is cooled to (say) 500° F. The mazout at this temperature then goes through heat exchanger 65, where it exchanges heat with crude oil as previously described. The mazout leaves this exchanger at about 360° F. and then goes through exchanger 66, wherein it is heated to about 480° F.

By this arrangement of exchangers, the mazout at its highest temperature does not directly heat the crude oil, but directly heats a more advanced part of the stream of mazout and then, at a reduced temperature (say 500° F.), heats the crude oil and becomes then, at a still further reduced temperature, the said more advanced part of the stream of mazout which is heated by the mazout at its highest temperature. The effect, from one viewpoint, is the same as of the hot mazout exchanged heat directly with the crude and thereby had its temperature reduced from 130

(say) 580° F. to 480°; but the described more roundabout heat transfer avoids subjecting the crude to a temperature in excess of 500° F. I have found that if the crude is subjected to a temperature in excess of about 5 500° F., it so locally overheats the film of oil adjacent the heated surface of the passage through which the crude flows that a deposit of salt is formed in the exchanger on the crude oil side. By the indirect heat transfer 10 described, this highly objectionable condition does not occur.

Leaving exchanger 66, the intermediate mazout passes through line 99 and into tank 15 103 or tank 104, in which tank it is mixed with approximately one per cent of 38° Bé. soda. The soda is pumped into the tanks through line 107 and is therein thoroughly mixed with the oil by circulation through 20 pumps 108 and 109. The provision of two tanks arranged as shown affords a convenient means of avoiding a break in the continuity of the process. The oil from line 99 is run (say) into tank 103 until it is practically full, 25 all the air in this tank having been expelled by steam. The soda is then admitted through line 107. A pressure of (say) 360 pounds gauge is immediately generated, due to the vapor pressure of the water in the soda at 30 this temperature. Pump 108 is then started and the mixture of oil and soda circulated through line 105 back to the tank and through line 105 again. This operation should be continued for about ten minutes, or such other 35 and usually longer time as may be required to give an intimate mixture of soda and oil and to enable the soda to neutralize any acidity that may be in the oil. As an excess amount of soda is preferentially used, the 40 mixture will be alkaline.

Having thus obtained the mixture, the valve on line 105 is shut and the mixture is pumped through line 110 to tower 111. The 45 time of pumping out tank 103 is so arranged that the same time interval will enable a fresh charge to be treated in tank 104. Thereby a continuous feed may be obtained in line 110.

The mixture of soda and oil under pressure 50 goes through line 110 to vaporizing tower 111, which is maintained at a substantially reduced—preferably atmospheric—pressure. Due to this reduction in pressure, enough specific heat is converted into latent heat to 55 permit all the water which is in the soda that will boil at a temperature of 460° F. to be vaporized. It is desirable to remove this water to as great a degree as possible to enable a greater vacuum to be obtained in the 60 subsequent distillation of the lubricating fractions. This object tower 111 successfully accomplishes.

It is difficult to get an intimate mixture 65 between the oil and the soda when only a small proportion of the latter is added. How-

ever, in my process, I secure the advantage of a larger amount of liquid caustic soda, as it is mixed, in tanks 103 and 104, under such conditions of pressure and temperature that the water will not vaporize. Then, in tower 70 111, the water which would be highly objectionable at a later stage of the process is removed.

The steam generated in tower 111 passes upwards through manifolds 112 into condenser 113. The mazout and soda mixture passes out through line 114 and pump 115 through back-pressure valve 140 into tank 116, where the oil is flowed over vaporizing pans. This tank is maintained under a substantial 80 vacuum, say of 28 inches. Due to the reduction in pressure from atmospheric, or about 15 pounds absolute, to about two pounds absolute, enough sensible heat is converted into latent heat to enable all the gas oil left in the 85 mazout from the topping process to be vaporized and pass out through line 118 into tower 119.

Due to the great velocities at which vapors form and leave the surface of the oil in the 90 vaporizing pans of tank 116, some entrainment of heavier oil may occur. The reflux condenser 120 at the top of tower 119 permits, by temperature control, the lighter products to pass out through line 121 and throws the heavy products back down into trap 124, from which, should the entrainment 95 be particularly objectionable, the heavier products flow back to the vaporizer; or, should the entrainment not be objectionable, such heavier products flow into a cooler 123, where they mix with the overhead distillate flowing through line 121, condenser 122 and cooler 123 into receiving tank 125. A vacuum is maintained on this tank by means of 100 vacuum equipment 127. The oil is pumped from tank 125 by means of pump 126.

The oil leaving tank 116 through line 117 is now in condition to be subjected to fractional distillation for the production of lubricating distillates and high grade asphalt. 110

Referring now more particularly to Figs. 1, 2 and 3, the oil from pipe 117 enters the vaporizing chamber *y* of the first (11) of a series of vaporizers wherein the lightest fraction of the oil is vaporized. The residue flows out through a pipe *b* into the next vaporizer 12 of the series wherein another, and somewhat heavier, fraction is vaporized. The residue then flows out through a pipe *c* 115 into the next vaporizer 13 of the series, wherein another, and still heavier fraction is vaporized. There may be as many vaporizers, 11, 12, 13, 14, etc., as may be desired. It is preferable to provide as many vaporizers as there are distillates to be produced; but the vapors from a single still may be subjected 120 to fractional condensation; or the vapors from different parts of the same still may be 125 separately condensed.

The final residue flows out through pipe *d* of boilers, operating under different pressures, into a tank *e* which may be connected to a vacuum pump through a pipe *f*.

The heating medium that I employ is mercury vapor, or any vaporizable metal, metallic compound, or other substance, such as possibly diphenyl oxide, benzo phenone, sulfur, or some possible metal alloy, that may be found to possess those characteristics of mercury vapor that make it particularly adapted to the purpose of the present invention. In claiming mercury vapor, it is intended to include any substance that may be, in fact, an equivalent. These characteristics principally are: (1) its boiling points, at practicable absolute pressures, correspond to temperatures desirable in oil distillation; (2) it may be brought as a vapor into heat exchange relation with the oil and, by regulating the pressure, may be caused to condense at the temperature desired and impart its latent heat to the oil; (3) the amount of heat transferrable to the oil with each degree of temperature difference between the mercury vapor and the oil is vastly greater than where a hot gas, such as steam or furnace gases is used as a heating medium; (4) nearly all its heat is usefully expended in heating the oil; (5) avoidance of local overheating due to high temperature differences between the heating medium and the oil; (6) economy in the amount of the heating medium required to vaporize a given amount of oil, thereby making it practicable to avoid the use of an apparatus of huge dimensions.

A commercially practicable mercury vapor distilling apparatus is shown in Fig. 3, which is set forth in detail in applications for patents filed by Pew and Thomas May 24, 1926, Serial Nos. 112,443 and 112,444, which matured into Patents 1,714,811 and 1,714,812 respectively on May 28, 1929. From a mercury boiler *g* extends a mercury vapor line *h* having branches extending to the mercury chambers *x* of the several vaporizers 11, 12, 13, etc., each of which branch pipes is equipped with a valve *i*, by means of which the rate of flow of the mercury vapor into the mercury vapor chamber of any vaporizer, and hence the pressure within the same and the temperature of condensation within the same and the heat to which the oil in such vaporizer is subjected, may be independently regulated. Extending from the mercury chamber of each vaporizer is a mercury condensate return, which comprises pipe *j*, cup *k*, goose-neck *m*, pipe *n* and vessel *o* communicating with boiler *g*. The connections shown are adapted not only to allow mercury condensate to return to the boiler but to provide balancing columns of liquid mercury to take care of pressure differences between the boiler and the mercury vapor chamber of each vaporizer. If desired, a plurality

of boilers, operating under different pressures, may be employed for different sets of vaporizers, but it is still desirable to utilize the described means for maintaining differential pressures in the boiler and in the mercury vapor chambers of the vaporizers in order to avoid unnecessary high temperatures of condensation in the mercury vapor chambers of the vaporizers of the set in which the lighter fractions of the oil are driven off.

From the mercury vapor supply line *h* extends a pipe *p* communicating with a pressure control valve *r* which opens when the boiler pressure exceeds the desired maximum and allows mercury vapor to flow past the valve into a condenser *s* which, through a goose-neck pipe *t*, communicates with the boiler *g* either directly or through the mercury condensate line *n*.

Each vaporizer 11, 12, 13, 14, etc. comprises a long tubular container, preferably oval in cross-section and divided, by means of a pan or partition *w* running lengthwise therethrough, into a mercury vapor condensing chamber *x* and an oil vaporizing chamber *y*. The oil flows onto and down over the pan *w* of each vaporizer in a comparatively thin stream and at a rapid rate, a minor fraction of the oil being vaporized in each vaporizer if, as is preferable, a separate vaporizer is provided for each desired distillate. A single very long vaporizer may be substituted and progressively heavier vapors may be taken off separately along the length of the vaporizer and separately condensed; or vapors may be taken off at different points along the length of a vaporizer and fractionally condensed; but, as above stated, it is preferable to provide one vaporizer for each distillate, thereby permitting a minimum effective temperature difference between the oil in any given vaporizer and the mercury vapor in such vaporizer. It is, however, highly desirable to provide a plurality of exit pipes *v* from the vaporizer, preferably a number of them at different parts along the length thereof, as shown in Fig. 2.

The arrangement is such that no heat is applied to the vapors after they leave the surface of the oil; no heat, in fact, being directly applied to any part of the oil except the film thereof that is, at any given moment, in contact with the pan or partition *w*. The temperature of the vapors, as they leave any vaporizing chamber *y*, is, in fact, very much below the temperature of any particle of liquid oil within the vaporizer.

Connected with the oil vaporizing chamber of each vaporizer is a condensing, refluxing and deodorizing apparatus. Each apparatus is like the others, so that a description of one will suffice for all. Such apparatus forms the subject-matter of applications filed by me May 29, 1926, Serial No.

112,485 and August 27, 1926, Serial No. 131,911.

The vapor from any vaporizer (say 11) escapes through pipes *v* to a header 18 and thence through pipes 19 to the lower part of a tower 20 (see Figs. 1, 2 and 4). Just above the discharge mouths of pipes 19, and not far above the bottom of the tower, is a grid 21, which supports a pile of chemical tiles, preferably the well known Raschig rings, 22. Above and spaced from the top of the pipe of tiles 22 is another grid 23, similar to grid 21. Grid 23 supports another and higher pile of tiles 24, which may be of the same character as tiles 22.

Below grid 23 and above tiles 22, and spaced from both, is a pan or partition 25 provided with an upstanding flange 26 enclosing a central vapor passage. Secured to the bottom of grid 23 is a deflector 27, which consists of an imperforate disc having a peripheral downwardly and obliquely extending flange whose periphery overhangs the annular space outside of the flange 26 of partition 25.

The bottom of the tower communicates, through a pipe 28, with one of the vaporizers, preferably the same vaporizer as that from which the vapors passed into the bottom of the tower, and with that end of such vaporizer into which the main stream of oil is fed.

The top of the tower communicates, through a pipe 29, with a stink oil receiver 35, to which is connected a pipe 36 connected with vacuum.

Any vapors carried into the tower 20 from pipes *v* that are heavier than the fraction which it is desired to segregate will condense while going through the tiles 22 and flow down to the bottom of the tower. Any particles of oil that may possibly be entrained with the vapors will also flow to the bottom of the tower. Thence the condensate, or condensate and unvaporized oil, will return to the vaporizer through pipe 28 and join the incoming stream of oil.

The uncondensed vapors will pass up through the central opening in pan 25, through the annular space around deflector 27 and through grid 23, and through the high pile of tiles 24, wherein the vapors are cooled and most of them condensed. The uncondensable gases escape through stink pipe 29 into the receiver 35. The condensate flows back through the tiles 24 and through the grid 23 into the annular oil receiving pan 25. Thence the condensate passes through a pipe 30 (having a goose-neck providing a trap 31) into what I call a deodorizer 40.

The distillate entering the deodorizer is in fairly good condition, but it carries with it some products that impart a somewhat undesirable odor to the oil and from which the oil should be freed.

The deodorizer 40 consists of an upright

chamber, rectangular in cross-section, and provided with inclined staggered flow plates 41 over which the distillate is distributed in very shallow streams and down which it flows at a velocity sufficient to create a substantial turbulence, or agitation, of the oil films. Let into the side of the chamber 40 are a series of outlet pipes 42, positioned respectively between adjacent plates 41. The outlet pipes 42 are connected to a header 43, which is connected, through a valved pipe 44, to a vacuum pump (not shown). The bottom of chamber 40 is connected, through pipe 49, with a receiver 50, which is connected, through a pipe 51, with a source of vacuum. The odoriferous gases are removed from the oil on each plate 41 and withdrawn from the receiver through pipes 42; the operation being such that there can be no reabsorption of gases in the oil. The oil passing into receiver 50 is ready for the market without further treatment.

It should be stated, at this point, that by reason of the conditions under which the oil is vaporized, the vapors that enter most of the towers 20 are wholly devoid of cracked products, although, possibly, in the latest vaporizer or vaporizers of the series, there may be some cracking but in an amount so small as not to produce decomposition products in quantity or character sufficient to appreciably affect the quality of the oil. It is difficult, however, in any of the vaporizers, to avoid the production, of, or, rather, the escape of, products that import an undesirable odor to the oil. These products are believed to be fixed gases and aromatic gaseous compounds present in the crude oil; or they may be produced in the gasoline and gas oil topping operations preparatory to feeding the oil to the first vaporizer 11 of the series, especially if the hereinbefore described topping process is not used. It is also quite possible that in all the vaporizers, as well as in the initial topping operations, there may be formed products produced by the breaking down of sulfur compounds. Whatever the character of the products may be that impart an undesirable odor to the lubricants distilled by the present process, they are mainly, and probably wholly, in gas phase. This is especially true of the fractional distillates that go to the deodorizers 40.

The operation in towers 20 and deodorizers 40 whereby these odor-producing gases are removed is in no sense a distilling operation; that is, neither the tower 20 nor the deodorizer 40 is a still. The operation of distilling involves the conversion of liquid to vapor, which operation is believed not to occur either in the towers or in the deodorizers. The conditions necessary for vaporization are not present in either; because, while there is a slight rise in vacuum, there is, at the same time, a very great drop in heat in the towers

and a slight drop in heat in the deodorizers. The distillate leaving the towers at 30 may be at a temperature from 150° to 200° F. lower than that of the vapors that enter the tower. What occurs in the towers is a separation of gases from oil vapors and from liquid oil. What occurs in the deodorizers is the further separation of gases from liquid oil. The separation in the towers is not complete, because the separated gases are being continually reabsorbed by downflowing condensate. The separation in the deodorizers is practically perfect, because no opportunity is afforded for reabsorption of released gases.

The percentage of these odor-producing gases is very small even in the vapors that enter the tower. The percentage of such gases in the distillate that flows out the tower to the deodorizer is much smaller. In fact, due to the high vacuum to which the distillate is subjected, its gas content must, of necessity, be extremely low. An extremely small proportion of odor-producing gases, however, suffices to impart a quite perceptible odor to the oil. By distributing the oil in thin films over plates 41 and agitating the films by maintaining them in motion along the plates and dropping them from one plate to another, every particle of liquid is exposed to an extremely high vacuum (say about 3 mm. mercury absolute pressure) under which conditions, although no vaporization may occur, no gas can remain in the oil. Consequently, the oil is entirely deprived of the products that impart to it a disagreeable odor.

If a narrow range cut is not desired, the whole product may be condensed and passed direct to the deodorizer 40. Whether or not the heavier constituents are refluxed and returned to the flowing stream of oil, the distillate need not be passed direct to the deodorizer 40, but may be temporarily stored and subsequently fed to the deodorizer at a regulated rate.

The highest degree of vacuum, which may be equal to an absolute pressure of (say) one to five millimetres mercury, is that operative on the deodorizer 40, tank *e*, and receivers 35 and 50, and particularly the deodorizer. Without objectionably large connecting pipes, there is some drop in the vacuum between the vacuum pumps and the oil vaporizing chambers of the vaporizers, particularly if a refluxing and condensing tower 20 is used; but it is quite possible, if the pressure in the parts of the apparatus directly connected with the pump is no higher than 7 mm. mercury absolute, to maintain a pressure within the oil vaporizing chambers of the vaporizers below, and even considerably below, 25 mm. mercury absolute.

The vaporizers need not be of any particular size, but vaporizers each 20 feet long, 5 feet high and 2½ feet wide, are practicable.

The vaporizers are so inclined as to have a fall of about one foot in 34 feet.

The temperature of the oil entering the first vaporizer of the series may be (say) 410° F. and that of the oil entering the last vaporizer of the series may be (say) 710° F. These figures are illustrative merely. The relatively high temperature in the last vaporizer of the series is substantially lower than that required to vaporize the heaviest constituents that are vaporizable in any ordinary distilling process. In fact, the oil, by my process, is capable of being distilled down to asphalt or coke, thereby producing new lubricants having characteristics heretofore unknown.

The oil may be admitted to the first vaporizer of the series at the rate of one hundred barrels (4200 gallons) per hour. The oil will occupy (say) about 5.9 seconds in traversing the chamber from one end to the other. The velocity of flow will be about 3.4 feet per second and the average depth on the pan will be about 13-60th of an inch. About twelve per cent., or twelve barrels per hour, will be vaporized and pass to the condenser. The residual oil that flows to the second vaporizer will have a temperature of (say) 450° F. The data given are merely illustrative, and moreover are based on the assumption that ten or twelve vaporizers having the same heating surfaces comprise the series. They give a good idea of desirable conditions of operation in the first vaporizer of the series. As the oil flows through successive vaporizers and is deprived of progressively heavier constituents, it becomes more viscous and less free flowing. The time occupied in flowing through a vaporizer, the velocity of flow, the depth of the oil stream, and the yield of distilled oil, all tend to decrease as the oil flows through successive vaporizers; but such decrease, at least so far as concerns all factors, is not necessarily constant or progressive.

The process adapted to be practiced in the described apparatus is one embodying all the factors required to establish an extremely high vacuum on every particle of the oil being vaporized, as well as all the factors required to avoid conditions tending to neutralize or impair the advantages of such a vacuum.

By utilizing the latent heat of mercury vapor liberated by its condensation to heat the oil fractions to vaporizing temperatures, not only is a greatly preponderant proportion of such heat usefully expended, but, by virtue of the provisions made for differentially regulating its rate of flow to the several vaporizers and the establishment therein of different pressures, and hence different temperatures of condensation, the maximum heat to which the oil in any vaporizer is subjected so closely corresponds to the temperature at

which the desired fraction of the oil vaporizers that local overheating is impossible.

The desirable depth of the oil body in any vaporizer is such that the hydrostatic pressure on such of the oil particles as are in actual contact with the pan or partition of the vaporizer is negligible. Indeed, while the stream of oil is necessarily thin, it may be substantially thicker than the fraction of an inch hereinbefore specified without producing a hydrostatic pressure at the "base" of the "column" that would materially lower the vacuum.

No heat is directly applied to any part of the oil except that which is transmitted through the pan along which the oil flows. Hence the vapors themselves are not subjected to heat. This feature is of the utmost importance, because there is abundant reason to believe that cracking occurs only in vapor phase. Hence, if the temperature be suitably controlled, the bottom of the oil film may be subjected to a temperature within a low cracking range without effecting cracking of the oil. It has been found that, in some of the vaporizers, there is a difference in temperature between the liquid oil and the oil as it escapes at the vapor outlets as high as 125° F. The specific process described is therefore far more effective than if the mercury vapor condensed on the surface of a tube through which oil and oil vapors were flowing; although, perhaps, it would be possible to so practice the process in the distillation of the lighter cuts. It would be quite feasible, however, to allow the oil to drop down over tubes through which mercury vapor is flowing and in which it is condensed. The heating, however, by means of furnace gases, whose heat conductivity is relatively very low, is impracticable, even if an absolute vacuum could be maintained in the tubes; because, in order to secure adequate heat transfer, either the temperature of the gases would have to be prohibitively high, or the total area of the heating surfaces would have to be so great as to involve the use of an apparatus of impracticable size.

The present process also embodies the important features of control of the temperature of the heating medium at its locus of heat transfer, thereby avoiding the use of a higher temperature than is required to drive off a predetermined fraction of oil. This factor is of importance in the distillation of those heavier fractions wherein a relatively high temperature of condensation of the mercury vapor is necessary, but wherein such temperature should be no higher than is necessary.

The present process also provides for extremely rapid and direct withdrawal of the oil vapors from the vaporizer, thereby not only avoiding the continued application of heat thereto, but avoiding also the building

up of pressure that would occur if, before their escape, they were required to travel for a substantial distance through a passage of restricted cross-sectional area along with the flowing body of oil.

It should be understood that in the distillation of the lightest fractions of the oil a high vacuum is not essential, owing to the fact that the boiling points of the vapors need not exceed a cracking temperature even with a low vacuum, or possibly even with no vacuum. It is also true that in the distillation of the lightest fractions it is of no special utility to provide for the condensation of the mercury vapor at the lowest temperature that is effective to distil such fractions, inasmuch as a somewhat higher temperature may not be an effective cracking temperature. All the factors characterizing the preferred embodiment of the present process are required only in the distillation of relatively high boiling point fractions. In distilling such fractions, not only should the pressure be maintained below about 25 mm. absolute but the difference between the temperature of the oil as it enters the space in which it is vaporized and the temperature at which the mercury vapor is condensed should not exceed about fifty degrees F. The application of the process to the distillation of the heaviest fraction of the oil produces distillates that heretofore have never been produced at all, because by no other process is it possible to drive them off without overheating to such an extent that they are decomposed into lighter viscosity products and obviously no subsequent re-distillations and chemical treatments can convert such products into high viscous lubricants.

As hereinbefore stated, if the vapors leaving some or all of the vaporizers are condensed without any treatment at all, they have a somewhat objectionable odor which, while not affecting their lubricating properties, may somewhat affect their marketability. It may be said, however, that, after the removal, in the last stage of the present process, of the odor producing gases, if a very small percentage of a distillate like that produced by ordinary processes be added to the oil produced by the present process, it produces an odor more objectionable than that which characterizes the oil that, in the present process, is produced by mere distillation. It is, therefore, clear that, in the present process, the proportion of odor producing products is very low. It seems probable, also, that they are composed, to a considerable degree, if not solely, of fixed gases and aromatic compounds present in the crude, or produced in the topping, or of broken down sulfur compounds that break down at a low temperature, because they are present to as great a degree, if not in a greater degree, in the lowest boiling distillates pro-

duced by the present process (which are not subjected to any temperature that could possibly produce cracking) as in the high boiling distillates. At any rate, they are products which are removed largely in the condensing process and completely in the special deodorizing process that constitutes the last step of the process; and such removal is effected as an integral part of the distilling process itself without any expense other than a capital expenditure that does not much exceed the cost of ordinary condensers.

It is also entirely practicable, in my process, to inject steam into the oil and thereby reduce its boiling point, as is well known in the art. Such use of steam, however, discolors the final products unless the steam be produced from water that has been thoroughly deaerated, as described in the patent issued to me April 2, 1929, No. 1,707,448.

It should be understood that while in certain claims I have claimed, as a part of the process, the preparation of the crude oil for distillation of lubricating fractions by subjecting it to certain treatments, it is not thereby intended to exclude the preliminary distillation of the lightest fractions by any method and the preparation of the residual oil for distillation of lubricating fractions by subjecting it to said treatments; the term "crude oil" being intended to include any oil which is in a crude state relatively to the residual oil which is adapted for distillation of lubricating fractions.

Where it is stated that the oil stream, in its progress through the apparatus, is confined against access of oxygen, it should be understood that it is intended to substantially exclude the admission of oxygen in such form, as by admission of air, as would cause the oxygen to combine with constituents of the oil and form objectionable oxidation products.

The entire process, starting with the crude oil and ending with the ultimate residue, is a continuous one and may be conducted in the single apparatus described. The necessary successive distillations, as well as the soda treatment and subsequent dehydration, are all so conducted, under such conditions of minimum temperature and controlled pressure, with exclusion of access of oxygen, as to prevent, or reduce to the lowest possible extent, the formation of cracked and oxidation products and to neutralize, to the greatest possible extent, any such products that may exist in the crude or be produced during the process. Finally, there are removed from the oil odor-producing gases that, whatever their origin may be, are contained in the distillates from the lubricating oil stills.

From the foregoing description it will be understood that the highest grade lubricating oil distillates cannot be produced by a perfect process of lubricating oil distillation

unless the distillations and treatments to which the crude oil is subjected are of such character as to provide a lubricating stock of proper quality. It will also be understood that high grade lubricating oil distillates cannot be produced from perfect lubricating stock unless the lubricating oil distillation process is so conducted as to prevent or minimize the formation of cracked and oxidation products that it is desired to exclude from the ultimate distillates. It will also be understood that perfect processes of preparing lubricating stock and distilling lubricating oils cannot effect the removal of certain odor-producing and color-deteriorating products contained in the crude oil or produced by the breaking down of sulfur compounds. The various steps of the complete process embodying this invention are, therefore, all interrelated. This interdependence of the various steps of the entire process may be made still more clear by the statement that the various operations preceding the lubricating oil distillation present no substantial advantage over known operations so far as concerns the production of gasoline, gas oil and other relatively low boiling constituents, but are practiced solely for the purpose of producing a lubricating stock from which it is possible to make the highest grade lubricating oils. These operations are therefore a part of, or necessarily preliminary to, the process of manufacturing lubricating oil distillates.

That part of the herein described process which comprises the production of a lubricating oil stock substantially free of all impurities except certain odor-producing and color-deteriorating products, namely, that part of the process which is herein described as being practiced in the apparatus shown in Fig. 5A and in that part of Fig. 5B preceding the introduction of the oil to the first vaporizer of the lubricating oil distillation plant, is not herein claimed per se, but forms the subject-matter of an application filed December 22, 1926, Serial No. 156,287, which shows and describes the same apparatus and process, and of an application filed February 28, 1928, Serial No. 257,559, which shows and describes an embodiment of the same apparatus and process in an improved form.

Nor do I claim herein certain features of the within described process involving, inter alia, the vaporization of the oil by means of mercury vapor and which may be carried out in that part of the lubricating oil distillation unit illustrated in Fig. 3; certain features of this part of the herein described process forming the subject-matter of an application filed by Pew and Thomas March 5, 1925, Serial No. 13,040.

That part of the herein described process which comprises subjecting oil, from which all constituents, except odor-producing gases

of lower boiling point than that of the desired lubricating oil have been removed, to such heat and low sub-atmospheric pressure as will vaporize the desired hydrocarbons 5 without cracking, followed by subjecting the mixed vapors and gases to reflux condensation under a somewhat lower sub-atmospheric pressure but also at such reduced temperature as to prevent further vaporization and 10 effect condensation of substantially all the vapors except odor-producing gases, which condensate and separated gases are separately removed, is not herein claimed per se, the same forming the subject-matter of a division 15 hereof filed Feb. 28, 1930, Serial No. 432,085.

Having now fully described my invention, what I claim and desire to protect by Letters Patent is:

- 20 1. The process of producing lubricating oil distillates from crude oil which comprises preliminarily heating the oil and settling out water and sediment, flowing the oil in a continuous stream of restricted cross section 25 while heating the oil sufficiently to vaporize relatively low boiling oil fractions but not sufficiently to produce substantial cracking, separating and condensing oil vapors, establishing a flowing stream of hot residual oil, 30 intimately mixing therewith a solution of an acid-neutralizing material, distributing the mixture of oil and solution over an extended surface and without substantial application of heat evaporating the solvent of the acid 35 neutralizer, distributing the solvent-free oil over an extended surface while subjecting it to a vacuum sufficiently high, without the application of heat, to vaporize relative higher boiling oil fractions, flowing a stream of residual oil through, and distributing it over an 40 extended surface within, a confined space, flowing mercury vapor into heat exchange relation with the oil so distributed and flowing over said surface, so limiting the temperature 45 of the mercury vapor and the absolute pressure on the oil as to effect, by heat exchange and condensation of mercury vapor, the vaporization of oil while minimizing cracking, subjecting the oil vapors in a distributed condition to reflux condensation and under a 50 vacuum sufficient to extract therefrom odor-producing gases, flowing oil so condensed in a shallow, turbulent stream over a series of extended surfaces within a confined space, and, 55 without substantial distillation of its liquid constituents, subjecting the oil to a vacuum sufficient to remove from the oil odor-producing gases, and preventing reabsorption of the gases from the oil by immediately withdrawing the gases from the confined space, and 60 substantially excluding access of oxygen to the oil during the specified treatments.

- 65 2. The process of distilling lubricating oil which comprises flowing a stream of oil continuously into, through and out of a con-

fined space and while passing through said space distributing the oil over, and maintaining the progressive travel of the oil over, a surface adapted to be heated, generating mercury vapor from a body of liquid mercury and flowing such vapor into heat exchange relation, but out of contact, with the oil that is so distributed and flowing over said surface, and effecting, by heat exchange and condensation of mercury vapor, the vaporization of oil, 70 maintaining all parts of the oil flowing through said space under an absolute pressure substantially less than 25 millimeters mercury, and condensing the mercury vapor as above specified at a temperature not over about 50 degrees F. in excess of the temperature of the oil entering said space, thereby effecting the distillation of relatively heavy fractions of the oil at temperatures so low that cracking is substantially prevented. 75

3. The process of producing lubricating oil distillates free from odor-producing gases which comprises subjecting liquid oil to thermal conditions adapted to produce condensable oil vapors containing odor-producing gases, removing the oil vapors and condensing them, and distributing condensate over an extended area and while so distributed subjecting it to a vacuum sufficiently high to remove therefrom odor-producing gases. 80

4. The process of producing lubricating oil distillates free from odor-producing gases which comprises subjecting liquid oil to thermal conditions adapted to produce condensable oil vapors containing odor-producing gases, removing the oil vapors and condensing them, flowing condensate in a shallow, turbulent stream over a series of extended surfaces within a confined space, and, without substantial distillation, subjecting the oil to a vacuum sufficiently high to remove odor-producing gases, and preventing reabsorption of the gases by the oil by immediately withdrawing the gases from the confined space. 100

5. The process of producing lubricating oil distillates free from odor-producing gases which comprises subjecting liquid oil to thermal conditions adapted to produce condensable oil vapors containing odor-producing gases, subjecting the oil vapors to reflux condensation and simultaneously therewith, under a high vacuum, effecting a partial removal of odor-producing gases, and flowing condensate from which the odor-producing gases have been partly removed over extended surfaces while under a vacuum sufficiently high to extract substantially all the remaining odor-producing gases, and immediately removing extracted gases from the region of the flowing stream to prevent their reabsorption. 115

6. The process of producing lubricating oil distillates free from odor-producing gases which comprises subjecting liquid oil to thermal conditions adapted to produce 120

condensable oil vapors containing odor-producing gases, subjecting the oil vapors to fractional reflux condensation, returning the heavier condensate to the stream of oil undergoing vaporization, and simultaneously with the condensation of the lighter condensate, and under a high vacuum, effecting a partial removal of odor-producing gases, and flowing the condensate from which such gases have been partly removed over extended surfaces while under a vacuum sufficiently high to extract substantially the remainder of such gases and simultaneously removing the extracted gases from the region of the flowing stream to prevent their reabsorption.

7. The process of distilling lubricating oil which comprises flowing a stream of oil continuously into, through and out of a confined space and while passing the oil through such space distributing it over a surface adapted to be heated, generating mercury vapor from a body of liquid mercury and flowing such vapor into heat exchange relation, but out of contact, with the oil that is so distributed and flowing over said surface, maintaining such temperature of the mercury vapor as to effect, by heat exchange and condensation of mercury vapor, the vaporization of oil, removing the oil vapors and condensing them, and distributing condensate over an extended area and while so distributed subjecting it to a vacuum sufficiently high to remove therefrom odor-producing gases.

8. The process of distilling lubricating oil which comprises flowing a stream of oil continuously into, through and out of a confined space and while passing the oil through such space distributing it over a surface adapted to be heated, generating mercury vapor from a body of liquid mercury and flowing such vapor into heat exchange relation, but out of contact, with the oil that is so distributed and flowing over said surface, maintaining such temperature of the mercury vapor as to effect, by heat exchange and condensation of mercury vapor, the vaporization of oil, removing the oil vapors and condensing them, flowing condensate in a shallow, turbulent stream over a series of extended surfaces within a confined space, and, without substantial distillation, subjecting the oil to a vacuum sufficiently high to remove odor-producing gases, and preventing reabsorption of the gases by the oil by immediately withdrawing the gases from the confined space.

9. The process of distilling lubricating oil which comprises flowing a stream of oil continuously into, through and out of a confined space and while passing the oil through such space distributing it over a surface adapted to be heated, generating mercury vapor from a body of liquid mercury and flowing such vapor into heat exchange relation, but out of contact, with the oil that is so distributed and

flowing over said surface, maintaining such temperature of the mercury vapor as to effect, by heat exchange and condensation of mercury vapor, the vaporization of oil, effecting a partial removal of odor-producing gases, and flowing condensate from which the odor-producing gases have been partly removed over extended surfaces while under a vacuum sufficiently high to extract substantially all the remaining odor-producing gases, and immediately removing extracted gases from the region of the flowing stream to prevent their reabsorption.

10. The process of distilling lubricating oil which comprises flowing a stream of oil continuously into, through and out of a confined space and while passing the oil through such space distributing it over a surface adapted to be heated, generating mercury vapor from a body of liquid mercury and flowing such vapor into heat exchange relation, but out of contact, with the oil that is so distributed and flowing over said surface, maintaining such temperature of the mercury vapor as to effect, by heat exchange and condensation of mercury vapor, the vaporization of oil, subjecting the oil vapors to fractional reflux condensation, returning the heavier condensate to the stream of oil undergoing vaporization, and subjecting the lighter condensate, while in a distributed condition, without substantial distillation, to a vacuum sufficiently high to remove therefrom odor-producing gases.

11. The process of distilling lubricating oil which comprises flowing a stream of oil continuously into, through and out of a confined space and while passing the oil through such space distributing it over a surface adapted to be heated, generating mercury vapor from a body of liquid mercury and flowing such vapor into heat exchange relation, but out of contact, with the oil that is so distributed and flowing over said surface, maintaining such temperature of the mercury vapor as to effect, by heat exchange and condensation of mercury vapor, the vaporization of oil, subjecting the oil vapors to fractional reflux condensation, returning the heavier condensate to the stream of oil undergoing vaporization, and simultaneously with the condensation of the lighter condensate, and under a high vacuum, effecting a partial removal of odor-producing gases, and flowing the condensate from which such gases have been partly removed over extended surfaces while under a vacuum sufficiently high to extract substantially the remainder of such gases and simultaneously removing extracted gases from the region of the flowing stream to prevent their reabsorption.

12. The process of distilling lubricating oil which comprises flowing a stream of oil continuously into, through and out of a confined space and while passing the oil through such

- space distributing it over a surface adapted to be heated, generating mercury vapor from a body of liquid mercury and flowing such vapor into heat exchange relation, but out of contact, with the oil that is so distributed and flowing over said surface, maintaining such temperature of the mercury vapor as to effect, by heat exchange and condensation of mercury vapor, the vaporization of oil, removing the oil vapors and condensing them, distributing condensate over an extended area at a locus removed from said locus of heating and vaporization, and maintaining an absolute pressure of substantially less than 25 millimeters mercury upon the oil stream, oil vapors and condensate, thereby enabling relatively high boiling fractions to be distilled at temperatures so low that cracking is avoided or minimized and enabling odor-producing gases to be removed without substantial distillation. 10
13. The process of producing lubricating oil distillates from crude oil which comprises: first, preparing lubricating stock by subjecting the oil to conditions of heat and pressure adapted to vaporize lighter fractions while confining the oil against access of oxygen to thereby avoid any substantial production of oxidation products and thereby vaporizing such lighter fractions, and withdrawing the vapors; second, while continuing to confine the oil against access of oxygen, subjecting the residual lubricating stock thus produced to conditions of heat and pressure adapted to vaporize lubricating oil fractions and thereby producing condensable lubricating oil vapors containing odor-producing gases; and third, while continuing to confine the oil against access of oxygen, condensing lubricating oil vapors containing such gases and distributing the condensate over an extended surface at a locus removed from the locus of vaporization and while so distributed subjecting it to a high vacuum and thereby, without substantial distillation, removing odor-producing gases. 20
14. The process of producing lubricating oil distillates from crude oil which comprises: first, preparing lubricating stock by subjecting the oil to conditions of heat and pressure adapted to vaporize lighter fractions while confining the oil against access of oxygen to thereby avoid any substantial production of oxidation products and thereby vaporizing such lighter fractions, and withdrawing the vapors; and second, flowing a stream of the residual lubricating stock thus produced continuously into, through and out of a confined space also confined against access of oxygen and while passing through said space distributing the oil over, and maintaining the progressive travel of the oil over, a surface adapted to be heated, generating mercury vapor from a body of mercury and flowing such vapor into heat exchange relation, but out of contact, with the oil that is so distributed and flowing over said surface, maintaining such limited temperature of the mercury vapor and such limited absolute pressure on the oil as to effect, by heat exchange and condensation of mercury vapor, the vaporization of the oil while minimizing cracking, and removing the oil vapors and condensing them and throughout the process confining the oil and oil vapors against any substantial access of oxygen adapted to effect substantial production of oxidation products. 30
15. The process of producing lubricating oil from crude oil which comprises: first, preparing lubricating oil stock by subjecting the oil to conditions of heat and absolute pressure adapted to vaporize lighter fractions without substantial cracking and thereby vaporizing such lighter fractions and withdrawing the vapors; second, subjecting the residual lubricating stock thus produced to conditions of heat and absolute pressure adapted to minimize cracking and vaporize lubricating oil fractions and thereby producing condensable lubricating oil vapors approximately free from cracked products but containing odor producing gases; and third, condensing lubricating oil vapors containing such gases and distributing the condensate over an extended surface at a locus removed from the locus of vaporization and while so distributed subjecting it to a high vacuum and thereby, without substantial distillation, removing odor-producing gases and throughout the process confining the oil and oil vapors against any substantial access of oxygen adapted to effect substantial production of oxidation products. 40
16. The process of producing lubricating oil from crude oil which comprises: first, preparing lubricating oil stock by subjecting the oil to conditions of heat and absolute pressure adapted to vaporize condensable lighter fractions without substantial cracking and thereby vaporizing such fractions, and withdrawing the vapors; and second, flowing a stream of the lubricating stock so produced continuously into, through and out of a confined space and while passing through said space distributing the oil over, and maintaining the progressive travel of the oil over, a surface adapted to be heated, generating mercury vapor from a body of mercury and flowing such vapor into heat exchange relation, but out of contact, with the oil that is so distributed and flowing over said surface, maintaining such limited temperature of the mercury vapor and such limited absolute pressure on the oil as to effect, by heat exchange and condensation of mercury vapor, the vaporization of the oil while minimizing cracking, and removing the oil vapors and condensing them and throughout the process confining the oil and oil vapors against any substantial access of oxygen adapted to effect substantial production of oxidation products. 50
17. The process of producing lubricating oil distillates from crude oil which comprises: 55

- first, preparing lubricating stock by subjecting the oil to conditions of heat and absolute pressure adapted to vaporize lighter fractions while substantially avoiding cracking and while confining the oil against access of 5 oxygen, whereby the production of cracked and oxidation products is substantially prevented and thereby vaporizing, such fractions and withdrawing the vapors; second, subjecting the residual lubricating stock thus 10 produced to conditions of heat and pressure adapted to minimize cracking and vaporize lubricating oil fractions and thereby producing condensable lubricating oil vapors approximately free from cracked products but 15 containing odor-producing gases while continuing to confine the oil against access of oxygen; and third, condensing lubricating oil vapors containing such gases and distributing the condensate over an extended 20 surface at a locus removed from the locus of vaporization and while so distributed subjecting it to a high vacuum and thereby, and without substantial distillation, removing 25 odor-producing gases.
18. The process of producing lubricating oil distillates from crude oil which comprises: first, preparing lubricating stock by subjecting the oil to conditions of heat and absolute 30 pressure adapted to vaporize lighter fractions while substantially avoiding cracking and while confining the oil against access of oxygen, and thereby vaporizing said fractions and withdrawing the vapors, whereby 35 the production of cracked and oxidation products is substantially prevented; and second, flowing a stream of the residual lubricating stock thus produced continuously into, through and out of a confined space also confined against access of oxygen and while passing through said space distributing the oil over, and maintaining the progressive travel 40 of the oil over, a surface adapted to be heated, generating mercury vapor from a body of mercury and flowing such vapor into heat exchange relation, but out of contact, with the oil that is so distributed and flowing over said surface, maintaining such limited temperature of the mercury vapor and such limited 45 absolute pressure on the oil as to effect, by heat exchange and condensation of mercury vapor, the vaporization of the oil while minimizing cracking, and removing the oil vapors and condensing them. 50
55. 19. The process of producing lubricating oil distillates from crude oil which comprises: first, preparing lubricating stock by first heating the oil while it flows rapidly in a continuous stream of restricted cross-section at a temperature sufficiently high to effect vaporization of relatively lower boiling constituents and sufficiently low to avoid substantial cracking, removing and condensing vapors, then 55 distributing residual oil over an extended surface while subjecting it to a substantial vacu-
- um and while continuing to so limit the temperature as to avoid substantial cracking, removing and condensing vapors; second, subjecting the residual lubricating stock thus produced to conditions of heat and absolute 70 pressure adapted to minimize cracking and produce condensable oil vapors approximately free from cracked products but containing odor producing gases; and third, condensing lubricating oil vapors and distributing the condensate over an extended surface at a locus removed from the locus of vaporization and while so distributed subjecting it to a high vacuum and thereby, without substantial 75 distillation, removing odor-producing gases and throughout the process confining the oil and oil vapors against any substantial access of oxygen adapted to effect substantial production of oxidation products.
20. The process of producing lubricating oil distillates from crude oil which comprises: first, preparing lubricating stock by first heating the oil while it flows rapidly in a continuous stream of restricted cross-section at a temperature sufficiently high to effect vaporization of relatively lower boiling constituents and sufficiently low to avoid substantial cracking, removing and condensing vapors, then 80 distributing the condensate over an extended surface at a locus removed from the locus of vaporization and while so distributed subjecting it to a high vacuum and thereby, without substantial distillation, removing odor-producing gases and throughout the process confining the oil and oil vapors against any substantial access of oxygen adapted to effect substantial production of oxidation products.
21. The process of producing lubricating oil distillates from crude oil which comprises: first, preparing lubricating oil stock by first heating the oil, while it flows rapidly in a continuous stream of restricted cross-section, at a temperature sufficiently high to effect vaporization of relatively lower boiling oil fractions and sufficiently low to avoid substantial cracking, removing and condensing vapors, then flowing away residual hot oil and mixing 90 it with an acid-neutralizing solution and dis-

tributing the oil over an extended area while it is subjected to sufficiently low absolute pressure to vaporize the solvent and also relatively higher boiling oil fractions and while continuing to so limit the temperature as to avoid substantial cracking, removing and condensing vapors; second, subjecting the residual lubricating stock thus produced to conditions of heat and absolute pressure adapted to minimize cracking and produce condensable oil vapors approximately free from cracked products but containing odor producing gases; and third, condensing lubricating oil vapors and distributing the condensate over an extended surface at a locus removed from the locus of vaporization and while so distributed subjecting it to a high vacuum and thereby, without substantial distillation, removing odor-producing gases and throughout the process confining the oil and oil vapors against any substantial access of oxygen adapted to effect substantial production of oxidation products.

22. The process of producing lubricating oil distillates from crude oil which comprises: first, preparing lubricating oil stock by first heating the oil, while it flows rapidly in a continuous stream of restricted cross-section, at a temperature sufficiently high to effect vaporization of relatively lower boiling oil fractions and sufficiently low to avoid substantial cracking, removing and condensing vapors, then flowing away residual hot oil and mixing it with an acid-neutralizing solution and distributing the oil over an extended area while it is subjected to sufficiently low absolute pressure to vaporize the solvent and also relatively higher boiling oil fractions and while continuing to so limit the temperature as to avoid substantial cracking, removing and condensing vapors; and second, flowing a stream of the lubricating stock so produced continuously into, through and out of a confined space and while passing through said space distributing the oil over, and maintaining the progressive travel of the oil over, a surface adapted to be heated, generating mercury vapor from a body of mercury and flowing such vapor into heat exchange relation, but out of contact, with the oil that is so distributed and flowing over said surface, maintaining such limited temperature of the mercury vapor and such limited absolute pressure on the oil as to effect, by heat exchange and condensation of mercury vapor, the vaporization of the oil while minimizing cracking, and removing the oil vapors and condensing them and throughout the process confining the oil and oil vapors against any substantial access of oxygen adapted to effect substantial production of oxidation products.

23. The process of producing lubricating oil which comprises: first, preparing lubricating oil stock by first heating the oil, while

it flows rapidly in a continuous stream of limited cross-section, at a temperature sufficiently high to effect vaporization of the relatively lower boiling oil fractions and sufficiently low to avoid substantial cracking, removing and condensing vapors, then flowing away residual hot oil and mixing it with an acid-neutralizing solution, distributing the oil over an extended area and vaporizing off solvent while continuing to so limit the temperature as to avoid substantial cracking, and then distributing the oil over an extended area under a reduced and sub-atmospheric pressure and thereby vaporizing relatively higher-boiling oil fractions while continuing to so limit the temperature as to avoid substantial cracking, and removing and condensing vapors; second, subjecting the residual lubricating stock thus produced to conditions of heat and absolute pressure adapted to minimize cracking and produce condensable oil vapors approximately free from cracked products but containing odor producing gases; and third, condensing lubricating oil vapors and distributing the condensate over an extended surface at a locus removed from the locus of vaporization and while so distributed subjecting it to a high vacuum and thereby, without substantial distillation, removing odor-producing gases and throughout the process confining the oil and oil vapors against any substantial access of oxygen adapted to effect substantial production of oxidation products.

24. The process of producing lubricating oil which comprises: first, preparing lubricating oil stock by first heating the oil, while it flows rapidly in a continuous stream of limited cross-section, at a temperature sufficiently high to effect vaporization of the relatively lower boiling oil fractions and sufficiently low to avoid substantial cracking, removing and condensing vapors, then flowing away residual hot oil and mixing it with an acid-neutralizing solution, distributing the oil over an extended area and vaporizing off solvent while continuing to so limit the temperature as to avoid substantial cracking, and then distributing the oil over an extended area under a reduced and sub-atmospheric pressure and thereby vaporizing relatively higher boiling oil fractions while continuing to so limit the temperature as to avoid substantial cracking, and removing and condensing vapors; and second, flowing a stream of the lubricating stock so produced continuously into, through and out of a confined space and while passing through said space distributing the oil over, and maintaining the progressive travel of the oil over, a surface adapted to be heated, generating mercury vapor from a body of mercury and flowing such vapor into heat exchange relation, but out of contact, with the oil that is

so distributed and flowing over said surface, maintaining such limited temperature of the mercury vapor and such limited absolute pressure on the oil as to effect, by heat exchange and condensation of mercury vapor, the vaporization of the oil while minimizing cracking, and removing the oil vapors and condensing them and throughout the process confining the oil and oil vapors against any substantial access of oxygen adapted to effect substantial production of oxidation products.

25. The process of producing lubricating oil which comprises: first, preparing lubricating oil stock by first heating the oil, while it flows rapidly in a continuous stream of restricted cross-section, at a temperature sufficiently high to effect vaporization of relatively lower boiling oil fractions and sufficiently low to avoid substantial cracking, removing and condensing vapors, then flowing away residual hot oil and mixing it with an acid-neutralizing solution and without substantial application of heat distilling off the solvent and also relatively higher boiling oil fractions, the distillation of the latter being effected under a low sub-atmospheric pressure by conversion of sensible heat of the oil into latent heat, and throughout the above specified operations confining the oil against access of oxygen and thereby avoiding any substantial production of oxidation products; second, subjecting the residual lubricating stock thus produced to conditions of heat and pressure adapted to minimize cracking and produce condensable oil vapors approximately free from cracked products but containing odor-producing gases while continuing to confine the oil against access of oxygen; and third, condensing lubricating oil vapors and distributing the condensate over an extended surface at a locus removed from the locus of vaporization and while so distributed subjecting it to a high vacuum and thereby, and without substantial distillation, removing odor-producing gases.

26. The process of producing lubricating oil which comprises: first, preparing lubricating oil stock by first heating the oil, while it flows rapidly in a continuous stream of restricted cross-section, at a temperature sufficiently high to effect vaporization of relatively lower boiling oil fractions and sufficiently low to avoid substantial cracking, removing and condensing vapors, then flowing away residual hot oil and mixing it with an acid-neutralizing solution and without substantial application of heat distilling off the solvent and also relatively higher boiling oil fractions, the distillation of the latter being effected under a low sub-atmospheric pressure by conversion of sensible heat of the oil into latent heat, and throughout the above specified operations confining the oil against access of oxygen and thereby avoiding any substantial production of oxidation prod-

ucts; and second, flowing a stream of the residual lubricating stock thus produced continuously into, through and out of a confined space also confined against access of oxygen and while passing through said space distributing the oil over, and maintaining the progressive travel of the oil over, a surface adapted to be heated, generating mercury vapor from a body of mercury and flowing such vapor into heat exchange relation, but

70 out of contact, with the oil that is so distributed and flowing over said surface, maintaining such limited temperature of the mercury vapor and such limited absolute pressure on the oil as to effect, by heat exchange and condensation of mercury vapor, the vaporization of the oil while minimizing cracking, and removing the oil vapors and condensing them.

27. The process of producing from crude oil lubricating oil substantially devoid of cracked products and disagreeable odor which comprises so heating the oil and at such temperature as to vaporize comparatively low boiling hydrocarbons without substantial cracking and removing said vapors so as to leave a heated residual oil not substantially above its cracking temperature, driving off progressively heavier hydrocarbons from the hot residual oil in a series of vaporizing operations in the earlier of which the absolute pressure on the oil is so substantially reduced as to effect partial vaporization of higher boiling hydrocarbons without substantial cracking and in the later of which the oil is subjected to such heat at such low absolute pressure as to effect partial vaporization of still higher boiling fractions without substantial cracking, condensing the oil vapors produced in the later vaporizing operation and placing the condensate, without the application of heat, under such high vacuum and at such temperature below that of the later vaporizing operation as to effect the removal of odor-producing gases without substantial evaporation of the liquid constituents of the condensed oil, and throughout the process confining the oil against any substantial access of oxygen adapted to effect substantial production of oxidation products.

In testimony of which invention, I have 115 hereunto set my hand, at Philadelphia, Penna., on this 3rd day of January, 1927.
